US00D728110S

(12) **United States Design Patent**
Corbett, III et al.

(10) **Patent No.:** **US D728,110 S**
(b4) **Date of Patent:** **** Apr. 28, 2015**

(54) **STERILE SHEATH FOR WEARABLE MEDICAL IMAGING INSTRUMENT**

(71) Applicant: **Sonivate Medical, Inc.**, Beaverton, OR (US)

(72) Inventors: **Scott Sutherland Corbett, III**, Portland, OR (US); **Martin Baumer**, Carlton, OR (US); **Alan Vernon Andresen**, Portland, OR (US); **William McDonough**, Portland, OR (US)

(73) Assignee: **Sonivate Medical, Inc.**, Beaverton, OR (US)

(**) Term: **14 Years**

(21) Appl. No.: **29/484,607**

(22) Filed: **Mar. 11, 2014**

(51) LOC (10) Cl. **24-01**

(52) U.S. Cl.

USPC **D24/187**; D24/105

(57) **CLAIM**

The ornamental design for a sterile sheath for wearable medical imaging instrument, as shown and described.

DESCRIPTION

FIG. 1 is a front perspective view of a sterile sheath for wearable medical imaging instrument showing our new design;

FIG. 2 is a top plan view thereof;

FIG. 3 is a side elevational view thereof;

FIG. 4 is a rear elevational view thereof; and,

FIG. 5 is a front elevational view thereof.

1 Claim, 1 Drawing Sheet
